(57) **CLAIM**

The ornamental design for an axle holder for motorcycle as shown and described.

DESCRIPTION

FIG. 1 is a front, left side, top perspective view showing my new design;

FIG. 2 is a front, right side, top perspective view thereof;

FIG. 3 is a front, left side, bottom perspective view thereof;

FIG. 4 is a front, right side, bottom perspective view thereof;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is a cross-sectional view thereof taken along at 11-11 of FIG. 5;

FIG. 12 is a cross-sectional view thereof taken along at 12-12 of FIG. 5;

FIG. 13 is a cross-sectional view thereof taken along at 13-13 of FIG. 5;

FIG. 14 is a cross-sectional view thereof taken along at 14-14 of FIG. 5; and,

FIG. 15 is a perspective view thereof in a state of use.

The broken lines in the drawings illustrate portions of the axle holder for motorcycle that form no part of the claimed design.

The continuous lines in the drawings represent an opening of the axle holder for motorcycle and form part of the claimed design. The fine lines on a surface of an inside of the opening in the drawings represent ridgelines that are curves of a solid surface.

The axle holder for motorcycle cools a brake caliper by straitening air that flows through the opening of the axle holder for motorcycle to an opposite side to a running direction of the motorcycle and by exposing the brake caliper to the air while the motorcycle runs.

1 Claim, 15 Drawing Sheets
